INVENTOR
Grover C. F. Mayer
BY
Wm. A. Courtland
ATTORNEY

UNITED STATES PATENT OFFICE.

GROVER C. F. MAYER, OF BROOKLYN, NEW YORK.

WINDOW GUARD.

Application filed October 27, 1921. Serial No. 510,961.

To all whom it may concern:

Be it known that I, GROVER C. F. MAYER, a citizen of the United States, residing in the borough of Brooklyn and State of New York, have invented certain new and useful Improvements in Window Guards, of which the following is a specification.

This invention relates to a window guard of the kind employed to prevent persons from falling through a window.

The primary object of the invention is to place within the casement outside the lower sash a guard that can be readily adjusted to position and removed therefrom at will.

Another object of the invention is to construct the several parts in such manner that they can be quickly assembled in position without cutting or marring the woodwork or attaching any part thereof to the casement.

Another object of the invention is to construct the guard in such manner that when the same is adjusted to assembled position it will be sufficiently strong to insure safety under all ordinary conditions.

Another object of the invention is to have the supporting casement strips, the guard rods and the binding nuts thereon so constructed and arranged that the entire guard can be quickly assembled and disassembled.

Other and further objects, including certain features of construction will appear in the specification and be pointed out in the appended claims, reference being had to the accompanying drawings which show the preferred embodiment of my invention.

In the accompanying drawings:

Figure 1 is a front elevation of a window casement showing the guard as placed in position.

Figure 2 is a transverse vertical section of Figure 1.

Figure 3 is a detail perspective view of a portion of the member which fits into the casement and receives the guard rods.

Figure 4 is an enlarged detail showing the guard rod, the nut and how said nut engages a casement strip.

Figure 5 is an enlarged detail sectional view of the nut and guard rod.

Figure 6 is a modified form of the nut.

In the preferred embodiment of my invention, 1 is the casement, 2 the sash guides, 3 the lower sash, 4 the upper sash and 5 the

window sill of a window of standard construction.

Fitted within the lower portion of the guideway 4' of the upper sash and within the casement are two wooden strips or members 6. These strips are preferably made of sufficient thickness to project somewhat inward beyond the sash strips 2. The lower ends of these strips rest on the window sill while the upper end terminates a short distance below the bottom of the upper sash. 65 These strips have therethrough holes 7, said holes being preferably four in number and equally spaced from the top to the bottom of said strips.

The guard rods 8 are suitably threaded 70 on their ends, as shown at 9, to receive the binding nuts 10. These nuts are internally threaded as shown at 11 to receive the rods 8 and also have on their ends heads 12 which fit into the holes 7 in the strip 6. 75 The body of each nut 10 is shouldered as shown at 13 for the purpose of engaging the strip 6 and forcing said strip into position in the casement at the same time tightening the rods between the two nuts. In 80 order to readily turn these nuts into position, a portion of the surface of same, as shown at 15, has been knurled.

The manner of assembling a guard with in a window, assuming the lower sash to be 85 raised as shown in Figure 2, is as follows. The strips 6-6 are placed within the lower portion of the upper sash guideways 4' so that the bottoms of the same rest on the window sill. Each rod 8, which has been 90 previously screwed within its nuts to the limit is held in horizontal position so that the head of each nut is adjacent a hole 7 in strip 6. The nuts are then screwed outwardly on the rod permitting the heads 12 95 to enter said holes 7 in strips 6. When the nuts are screwed outwardly on the rod a definite distance, the shoulders 13 of said nuts will engage the strips around the holes therein and force said strips tightly against 100 the casement, at the same time holding said rod rigidly between the strips. The same operation of engaging the rods through the medium of the nuts is continued until all of said rods are in the position shown in 105 Figure 1.

It should be understood that when the nuts are screwed inward on the rods, as

shown in dotted lines in Figure 1, the length of said rod and nuts will be less than the distance between the strips when said strips are in position in the casement. 30

- 5 While these rods are made strong enough to resist ordinary pressure brought against them in case of accident, they can be readily removed in case of fire or emergency by seizing the rod in the middle and pulling 10 same so that it will be buckled and then quickly removed from engagement with the strips.

It will be observed that the guard, after being secured to the casement will in no 15 manner interfere with the movement of the lower sash in view of the fact that the said guard is placed within the lower portion of the guideway of the upper sash.

In Figure 6, a modification is shown 20 wherein the nut 20 has a threaded opening 21 extending entirely therethrough. This nut has a head portion 22 which fits within a hole 7 of strip 6 and is also provided with a shoulder 23 which abuts the strip to 25 firmly hold the rod in place when the nut is tightly adjusted against said strip. Instead of using a knurled nut as shown in Figure 4, a wing nut 25 is employed for adjusting said rod to proper position. The

rods are of a length to permit them, when the nut is screwed fully back thereon, to be placed between the strips 6. 35

Of course, it should be understood that changes can be made in the construction and application of this guard without departing from the spirit of the invention. 40

I claim:—

A guard for windows, comprising members having holes therein and adapted to fit within the sash guideways of the casement, guard rods shorter than the distance between said members when said members are within the sash guideways, flanged nuts on the ends of said rods capable of being screwed onto said rods so that the distance between the outer ends of the heads of said nuts on the rods will be shorter than the distance between the members when said members are in position in the casement, and portions on the outer end of said nuts adapted to fit within the holes in said members when the nuts are screwed outward on said guard rods permitting the flanges on said nuts to engage the members and hold said rods and members firmly in desired 45 position. 50
